UNITED STATES PATENT OFFICE.

FREDERICK JAMES PARKS, OF CLEVELAND, OHIO.

MACHINE FOR MAKING ENVELOPES.

Application filed May 10, 1924. Serial No. 712,200.

My invention relates to machines for automatically feeding paper sheets, applying glue to certain portions thereof, and to turning over and sealing the same by means of the glue upon the body portion of the sheet. The apparatus shown in the accompanying drawings is particularly adapted for service in making envelopes and relates especially to improvements in a machine of this character shown in U. S. Letters Patent, No. 1,316,737, issued to me upon September 23, 1919; and also to a machine of this character shown in my pending application for U. S. Letters Patent, Serial No. 690,423, filed February 4, 1924. The improvements of this application consist in new means for gumming the side flaps and side tabs of the envelope blank whereby the same are secured to the envelope body to form the side closures; new means controlling the operation of said gumming means; a new and improved form of curling or turning knife for insuring the folding of the lateral side flaps down upon the envelope body; a new and improved arrangement of scoring and gumming mechanism, whereby the scoring is effected in advance of the gumming so as to obviate the fouling of the scoring mechanism by the gum; and other detailed arrangements shown in the accompanying drawings and hereinafter fully described. There is claimed in this application only the new and improved gumming features, which are illustrated in the accompanying drawings in connection with the manufacture of envelopes, although the same have a field of general application in applying glue to paper sheets.

The annexed drawings and the following description set forth in detail certain means embodying my invention, such means constituting, however, but one of the various forms in which the principle of the invention may be applied.

In said annexed drawings:

Figure 1 is a fragmentary plan section of an envelope machine embodying my improvements, the section being taken in the plane represented by the line I—I, Figure 2;

Figure 2 is a longitudinal vertical section, taken in the plane indicated by the line II—II, Figure 1;

Figure 3 is a diagrammatic representation

of an electrical circuit adapted to control the operation of the gumming devices;

Figure 4 is a fragmentary plan section, upon an enlarged scale, taken in the plane indicated by the line IV—IV, Figure 2;

Figure 5 is a fragmentary transverse vertical section, taken in the plane indicated by the line V—V, Figure 2;

Figure 6 is a transverse vertical section, taken in the plane indicated by the line VI—VI, Figure 2;

Figures 7, 8, 9 and 10 are fragmentary transverse vertical sections, upon an enlarged scale, taken, respectively, in the planes indicated by the lines VII—VII, VIII—VIII, IX—IX, and X—X, Figure 1;

Figure 11 is a fragmentary vertical longitudinal section, upon an enlarged scale, taken in the plane indicated by the line XI—XI, Figure 6, and showing the gumming device in its upper or non-operative position;

Figure 12 is a view similar to Figure 11, showing the gumming device in its lower or operative position;

Figure 13 is a front elevation of the elements shown in Figure 11.

Figure 14 represents a plan view of the envelope blank as it emerges from the folding device preparatory to being fed into the improved side sealing devices described, shown and claimed herein;

Figure 15 represents a plan view of the completely folded and gummed envelope as it passes from the devices forming the subject matter of this application.

Referring to the annexed drawings, in which the several elements are indicated by the same respective ordinals, in the different views, I indicate by the ordinal 2 an envelope blank in a certain condition, hereinafter fully described, which has been folded up so as to have a mouth closure flap detachably interlocked with an adjacent pocket, as fully shown and described in my said Patent No. 1,316,737 and said pending application Serial No. 690,423. The improvements of this application relate only to parts of the device adapted to complete the operations upon the envelope, all as will now be described in detail, having reference to the accompanying drawings.

The envelope blank 2, in the form shown in Fig. 14 but lacking the gum strips 34,

Figures 8, 9 and 10 emerges from the transverse folders (not shown in this application but shown, described and claimed in said Patent No. 1,316,737 and said application Serial No. 690,423) and is fed into the guide 16, Figs. 1 and 2, whence it is conducted into the bight of the upper and lower peripherally engaging rolls 17 and 18 whence emerging from which it is received upon the plate 19 over which it passes to certain scoring, gumming and side sealing devices which will now be described in detail.

The envelope blank 2, Figure 14, is fed over the plate 19 in certain scoring rolls 35 and 36, of which there are two pairs, the lower rolls 36 being formed with end flanges 36', Figure 7, against which the outer end face portions of the rolls 35 closely register to define the lateral edge flaps 32, plainly shown in Figure 14. The end faces of the upper rolls 35 prevent the turning in of the side flaps 32 further than the position shown in Fig. 7 until said side flaps 32 intersect the bevel faces 40 of portions 39^a of a pair 25 of turning knives 39, Figs. 8, 9 and 10, which progressively fold down the side flaps 32 until they are finally sealed down upon the envelope portions 29 and the glue 34 to produce the complete envelope 3 shown in 30 Fig. 15. During these operations the envelope is conveyed by upper rolls 21, 41, 43 and 45 and respectively cooperating lower rolls 22, 42, 44 and 46, over the plate 47 and passes therefrom to further rolls and a 35 stacking device, not forming part of this invention, and one specific form of which is plainly shown, described and claimed in said pending application Serial No. 690,423.

During its passage from the scoring rolls 35—36 to the turning knife 39, the portions of the blank 2 designated by the ordinal 29 are supplied with glue 34 by the following devices. Referring particularly to Figs. 5 and 6, it will be noted that suitably mounted 40 in the frame 1 of the machine is a solenoid 88 having a core 87 to the upper end of which is pivotally secured the free end of a bar 86 whose other end is secured to a transverse shaft 89 rotatably mounted in the frame 1. 45 Also secured to the shaft 89 and adjacent the two ends thereof are respective arms 90 and 90' having U-shaped outer ends between the members 94—94' of which are mounted respective rollers 91—91', as plainly shown in Fig. 2. Referring particularly to Figs. 2 and 6, it will be noted that a pair 50 of vertically-reciprocable columns 92—92' suitably guided by brackets 93—93' and frame bosses 102—102' are supported by the rollers 90—90', respectively, and in turn support in brackets 103 at their upper ends a transverse tubular shaft 84. Adjustably secured in brackets 104, supported by said transverse shaft 84 are a pair of depending 55 tubular supports 26 for gumming devices

25. These supports 26 communicate intermediate their upper and lower ends with tubular sections 26' connected by means of flexible tubes 27 with tubular elbow-sections 26^a which in turn receive suitable glue or 70 other gumming material from a source of supply (not shown) through conduits 27' of which fragmentary portions are shown in Fig. 2.

Referring particularly to Figs. 1 and 5, 75 it will be noted that a flat spring plate 85 suitably supported as hereinafter fully described, is formed at one edge into downwardly extending fingers or trips 23 and 24. The ends of these fingers 23 and 24 are adjacent the upper edge of a plate 55 over which the envelope blank 2 travels after emerging from the scoring rolls 35 and 36, and after traversing an intermediate metal bar or plate 20 hereinafter more fully described. 80 The lower ends of these trips 23 and 24 which contact with the plate 55 are longitudinally spaced, as plainly shown in Figs. 1 and 2 for a purpose hereinafter fully described. 90

Referring particularly to Fig. 5, it will be noted that mounted upon the intermediate plate 20 and electrically insulated therefrom by means of insulating spacers 76 and washers 77, is a transverse metal bar 75, Figure 95 1, upon which the spring plate 85 is mounted and secured by means of bolts 60, one of which forms a binding post to which an electric wire 80 is secured. Referring to the diagrammatic representation of an electric 100 circuit shown in Fig. 3, it will be noted that the wire 80 leads to a battery 81 and that a second wire 82 connects the battery 81 and the solenoid 88. A third wire 56 connects the solenoid 88 with a binding post 57 electrically connected with the plate 55. A plate of insulation 78, secured adjacent one transverse edge to the plate 20 by means of bolts 83 and adjacent the other edge to the plate 47 by means of bolts 61, insulates the frame 105 110 of the machine from the metallic elements forming the electric circuit which has just been described.

From the foregoing description and the accompanying drawing, it will be evident 115 that when the circuit is completed and the coil 88 is energized, the core 87 being drawn into the coil 88 will rock the shaft 89 so as to cause the arms 90—90' to lift the columns 92—92' and consequently the transverse 120 shaft 84 and the brackets 104, whereby the supports 26 and the gumming devices 25 will be raised into the position plainly shown in Figs. 2 and 11. This is the normal position of the gumming devices 25 and in this 125 position these devices 25 are non-operative, i. e. they do not feed gum. When the coil 88 is deenergized, the gumming devices fall by their own weight into the position shown in Figure 12, which is the gumming position, 130

against the weight or pull of the bar 86, core 87 and associated elements. How the circuit is opened and the coil 88 consequently deenergized will be hereinafter fully described. The detail construction of the gumming devices 25 will now be described.

Referring particularly to Figs. 11, 12 and 13, it will be noted that the main support 26 of the gumming devices is formed with an angular downwardly-extending lower portion 26' having an outlet 74 forming a nozzle. Normally this nozzle is closed by means of a gumming roller 65 mounted between the arms 67 of a rocking frame 66 pivoted upon a pin 68 which in turn is mounted in a bracket 69 secured to the support 26. The upper end of the rocking frame 66, in the normal non-operative position of the gumming devices, is disposed a spaced distance from the support 26, as plainly shown in Fig. 11. This spaced condition of the frame 66 is maintained by a spring 71 secured at its upper end to a bracket 71' secured to the support 26, the lower end of said spring 71 bearing with any desired pressure upon the frame 66, this tension being regulated by means of a screw 72, as plainly shown in Figs. 11 and 12. It is evident that when the support 25 is lowered so as to cause the gumming roller 65 to contact the surface 29 of the envelope blank 2,—which is the envelope in the condition shown in Fig. 14 without the gum 34—said roller 65 will swing away from the nozzle 74 a distance determined by the space between a screw 73 intersecting the frame 66, and the support 25. This distance between the screw 73 and the support 26 can be regulated by means of the screw 73, as will be readily understood.

Referring now to the medium by which the opening and closing of the electric circuit is controlled so as indirectly to control the feeding of the gum 34.

This control is through the medium of the spring fingers or trips 23 and 24. The lower ends of these fingers 23 and 24 lie in the path of the envelope blank 2 so that said envelope blank 2 passes under said lower ends and raises the spring trips 23 and 24 to break the circuit. Of course, this results in the deenergizing of the coil 88 and the consequent release of the columns 92—92' from the upward pressure caused by the pull of the coil 88 upon the core 87 so that said columns 92—92', under the force of gravity, are lowered and, consequently, the gumming devices 25 are lowered, which allows gum to escape from the nozzle 74 so soon as said rollers 65 encounter the envelope blank 2. The gumming devices 25 are so disposed that the gum from the nozzle 74 is deposited upon the longitudinally arranged portions 29 of the envelope 2 adjacent the portions thereof which have been scored by the rolls 35 and 36. These portions 29 are plainly

shown in Fig. 14. The mechanism shown is arranged so that these portions are parts of the envelope body, but, of course, it is entirely within the range of the invention to deposit glue 34 upon the side flaps 32. This deposit of the glue 34 will not occur until the forward edge of the envelope 2 has passed beneath both of the fingers 23 and 24. It is evident that until such action has taken place, the electric circuit will not be broken. The arrangement is such that by the time the circuit is thus broken a portion of the envelope blank 2 has passed forwardly of the gumming devices 25 and consequently the gum is deposited upon the portions 29 beginning at a point somewhat removed from the forward edge of the blank 2. Also, it is evident that the circuit will be again closed just so soon as the rear edge of the blank 2 passes from beneath the rear trip 23. The arrangement is such that the consequent stopping of the discharge of the gum takes place upon a portion of the blank 2 somewhat removed from the rear edge of said blank 2.

I wish to point out that I have positioned the scoring rolls 35 and 36 forwardly of the gumming devices 25. In so far as I am informed this is new, and also it is very important because thereby I obviate fouling the scoring devices with the gum which is what happens, and with a very great annoyance and loss of efficiency, when the scoring of the blanks is effected subsequent to the gumming, because, of course, the gum lies open and is exposed during the scoring operation since the scoring must be effected before the side enclosures 32 are folded down.

For the further purpose of obviating the inconvenience and delay caused by excessive fouling of the machine by gum, I have devised the two-part folding knife 39—39' hereinbefore mentioned. When the beveled curling face 40 is formed upon the body of the knife 39, the gum 34 will accumulate thereunder and cannot readily be completely removed. So I have spaced the portion 39^a of the knife from the body portion 39 thereof, as plainly shown in Figures 1, 8, 9 and 10, connecting the same by straps 37, so that through the medium of the opening 38 the gum can be readily and conveniently wiped off the knife 39—39'.

These knives 39 are secured by means of bolts 63, Fig. 1, to the frame 1; the longitudinal alignment of the knives being assured by means of strips 39' secured to an aligning member 39^a, the bolts 63 intersecting said straps 39'. By means of two series of transversely aligned holes 62 in the frame 1, the knives 39 can be adjusted for envelopes of varying widths. Other parts of the machine are adjustable for different size envelopes, for instance, the scoring rolls 35

can be transversely adjusted upon the shaft 48 to which they are secured by the keyway 48', a suitable size intermediate spacing roll 50 being substituted, these spacing rolls 50, as plainly shown and described in said pending application Serial No. 690,423, being resiliently confined between the pair of rolls 35, to allow for the accommodation of the thickness of the envelope 2 between the 10 roll 35 and the flange 36' of the roll 36, Fig. 7. The scoring rolls 36 are adjustably secured to a transverse shaft 49. The gumming devices 25 can be transversely adjusted upon the support 84. In order to accommodate the envelopes when passing between any of the cooperating parts of the rolls, the shafts to which the latter are secured are resiliently mounted in the frame 1 in yielding bearings pressed downwardly by means 20 of springs whose tension is adjusted by screws 53, the desired adjustment being fixed by means of lock nuts 54, Fig. 2.

Cooperative driving mechanism for actuating the feeding rolls, scoring rolls, etc, 25 are provided (not shown in detail in this application, but well known in various forms to those skilled in this art).

What I claim is:

1. In means for automatically applying 30 glue to paper sheets, the combination of sheet-conveying means; glue-feeding means; means forming a normally closed electric circuit including electrically-controlled devices holding said glue-feeding means in 35 non-feeding position, the arrangement being such that the travelling sheet cuts the circuit and holds it open temporarily; means closing said glue feeding means when the latter are in non-feeding position; means 40 permitting the glue-feeding means and the sheet to move into juxtaposition when the circuit is open; and means causing the glue-feeding means to function when the latter and said sheet are in juxtaposition.
2. In means for automatically applying 45 glue to paper sheets, the combination of sheet-conveying means; movable glue-feeding means; an electric circuit including devices holding said glue-feeding means in 50 non-operative position when the circuit is closed, a portion of the circuit consisting of a spring trip disposed in the path of the traveling sheet, said trip being moved by the sheet when the latter travels by, to open the 55 circuit, said glue-feeding means assuming operative position when the circuit is open; and means closing said glue feeding means when the latter are in non-feeding position, 60 said closing means being opened by contact with the glue receiving surface when said glue feeding means assume operative position.
3. In means for automatically applying 65 glue to paper sheets, the combination of sheet-conveying means; reciprocable glue-

feeding means per se maintaining a glue-feeding position adjacent the sheet, said gluing means comprising nozzles, glue ducts and supporting columns; an electric circuit including a solenoid, the core of the solenoid 70 when the coil is energized being adapted to move the supports of the gluing means upwardly so as to remove the glue nozzles from the sheet, the construction consisting of an assembly pivoted to a suitable support intermediate its ends and pivoted at one end to said solenoid core and disposed adjacently below said gluing means supports at its other end; and means controlled by the movement of the sheet for opening and closing the 80 circuit.

4. In means for automatically applying glue to paper sheets, the combination of sheet-conveying means; reciprocable glue-feeding means maintaining per se a glue-feeding position adjacent the sheet, said gluing means comprising nozzles, glue ducts and supporting columns; a normally closed electric circuit including a solenoid, the core of the solenoid when the coil is energized being 90 adapted to move the supports of the gluing means upwardly so as to remove the glue nozzles from the sheet, the construction consisting of an assembly pivoted to a suitable support intermediate its ends and pivoted 95 at one end to said solenoid core and disposed adjacently below said gluing means supports at its other end; and means adapted to close said nozzles when the glue-feeding means are out of contact with the sheet, the circuit being so arranged that the travelling sheet cuts the same and holds it open during a material part of its passage therethrough.

5. In means for automatically applying 105 glue to paper sheets, the combination of sheet-conveying means; movable glue-feeding means indirectly controlled by the movement of the sheet; an electric circuit directly controlling the movement of said glue-feeding means and adapted when closed to move the same to, and hold the same in, non-feeding position; a pair of trips adapted to intercept the sheet at longitudinally spaced points in its path of travel and be actuated thereby, the actuation of both trips by the sheet opening the circuit, the circuit being again closed when the sheet releases one trip, said glue-feeding means being permitted to assume feeding position under the influence 110 of gravity when the circuit is open.

6. In means for automatically applying 115 glue to paper sheets, the combination of sheet-conveying means; movable glue-feeding devices normally assuming under the influence of gravity a feeding position adjacent the sheet; a pair of trips adapted to intercept the sheet at longitudinally spaced points in its path of travel and be actuated thereby; an electric circuit of which said trips form a part in multiple; and electrical- 120 125 130

ly-controlled devices forming a part of said circuit and adapted when the circuit is closed to move said glue-feeding devices to, and retain them in, non-feeding position.

- 5 7. In means for automatically applying glue to paper sheets, the combination of sheet-conveying means; movable glue-feeding devices; a pair of trips adapted to intercept the sheet at longitudinally spaced points 10 in its path of travel and be actuated thereby; an electric circuit of which said trips form a part in multiple, said circuit including a solenoid; and an assembly pivoted at one end to the core of said solenoid, pivoted intermediate its end to a suitable support and disposed at its other end adjacently below said glue-feeding devices, the latter being free under the influence of gravity to assume feeding position adjacent the sheet when the 20 coil of the solenoid is deenergized.
8. In means for automatically applying glue to sheets, a glue-feeding device comprising a support formed with a glue duct having a discharge nozzle and a glue-applying roller pivotally mounted on said support and adapted when swinging freely to close said nozzle, the construction being such that, when said device is lowered to allow the roller to contact with the glue-receiving surface, the roller swings slightly away from the nozzle to allow glue to escape therefrom onto the glue-applying roller.
- 25 9. In means for automatically applying

glue to sheets, a glue-feeding device comprising a vertical support formed with a 35 downwardly inclined lower portion having a glue duct ending in a discharge nozzle; a bracket secured to said support; a frame pivoted intermediate its ends in said bracket; a glue-applying roller extending below the 40 plane of said nozzle and mounted in one end of said frame; and a spring secured to said support and acting upon the other end of said frame to hold the roller against the 45 nozzle to close the same.

10. In means for automatically applying glue to sheets, a glue-feeding device comprising a vertical support formed with a downwardly inclined lower portion having a 50 glue duct ending in a discharge nozzle; a bracket secured to said support; a frame pivoted intermediate its ends in said bracket; a glue-applying roller extending below the plane of said nozzle and mounted 55 in one end of said frame; a sheet spring secured to said vertical support and bearing against the other end of said frame to hold the roller against the nozzle to close the same; means for adjusting the spring tension against the frame; and means for adjusting the amount by which the nozzle may be opened when the roller is lowered to encounter the glue-receiving surface.

Signed by me this 15th day of April, 1924.

FREDERICK JAMES PARKS.
